Application December 10, 1958, Serial No. 53,724

Term of patent 14 years

(Cl. D26—14)

FIG. 1

FIG. 2

Des. 185,742

PAGE 2

FIG. 3

Fig. 1 is a side elevational view of a telephone mounting, showing our new design, the opposite side being substantially a mirror image thereof;

Fig. 2 is a front elevational view; and
Fig. 3 is a perspective view thereof.

The dominant features of our new design are shown in solid lines in the drawing. The broken line showing of a wire stub and handset are for illustrative purposes only. The drawing figures are stippled to indicate contrast in appearance.

We claim:

The ornamental design for a telephone mounting, substantially as shown and described.
